UNITED STATES PATENT OFFICE.

LOUIS JENSEN AND CHARLES L. WINTER, OF CHICAGO, ILLINOIS, ASSIGNORS TO UNITED AUTOGRAPHIC REGISTER COMPANY, OF CHICAGO, ILLINOIS, A CORPORATION OF ILLINOIS.

AUTOGRAPHIC REGISTER.

Application filed January 25, 1926. Serial No. 83,624.

The present invention relates generally to autographic registers, and similar devices, for performing the function of producing manifolding copies upon superposed continuous strips of paper, and the invention has more particular reference to devices of this general character that are adapted to wind up or otherwise retain a record strip within the casing of the machine. In the present structure this rewinding of the record strip is accomplished in conjunction with the re-starter devices and usual feed mechanism.

In manifolding machines for billing and the like, divers means have been employed to wind up or otherwise store the record or summary strip, which function is performed during the discharging of the tickets of the other strips, and to do this the winding shaft for the record strip is in some manner connected with the instrumentalities for moving the strips across the platen of the register. Frequently the winding shaft for the record strip, when the upper tickets are fed and discharged by the rotation of a crank or handle, is geared with the main drive or master feed shaft so that it will rotate more or less synchronously with said drive shaft, but such structures are objectionable because of the fact that during the re-winding of the record strip upon its spool the diameter of the roll of paper thereon, gradually increases and consequently a greater length of the record strip is pulled along at each rotation of the spool so that the strip will soon bind between its spool and the driving feed rollers. This inherent objection is successfully overcome by the herein described structure, and in this connection there is provided a geared connection between the driving feed rollers or their shaft and the shaft of the spool with a frictional connection between certain of the gears of the train, in combination with means for stopping the rotation of the record spool prior to the time when the upper tickets or strips have been discharged or fed the desired length through the machine. There is also provided adjustable means for predetermining the point of stoppage of the record re-wind spool with respect to the discharge of the upper tickets in order that the machine may readily adapt itself for use with tickets of divers

lengths. By stopping the rotation of the record re-wind spool prior to the completion of the feed of the upper tickets an amount of slack will be accumulated in the record strip between its re-wind spool and the driving feed rollers.

It is preferred to carry out this invention and to accomplish the divers objects thereof in substantially the manner hereinafter fully described and as more particularly pointed out in the claims, reference being here made to the accompanying drawings that form a part of this specification.

In the drawings:

Figure 1, is an end elevation of the discharge end of an autographic register showing the present improvements incorporated therewith, portions of the upper mechanism being in longitudinal section.

Figure 2 is a transverse section taken on line 2—2 of Figure 1 looking in the direction of the arrows.

Figure 3 is a detail view of the gear train upon the exterior of the casing or housing with the enclosure therefor in section.

Figure 4 is a schematic view of the gear train within the register casing or housing.

Figure 5 is a top plan of a modified form of our invention.

Figure 6 is a side elevation or detail of the modification shown in Figure 5.

Figure 7 is a transverse vertical section taken on line 7—7 of Figure 6.

Figure 8 is a fragmentary view of a paper strip such as used in the machine.

Figure 9 is a longitudinal section of the starting mechanism and assembled parts shown in Figure 5.

The drawings are merely schematic for the purpose of illustrating the principles of the present invention, and in said drawings similar reference characters have been employed to designate the same parts wherever they appear throughout the several views.

The present invention has herein been illustrated in connection with a re-starter mechanism that is employed to initially feed the strips so as to move the normally operating feed rollers or disks out of registration with perforations or punch-holes previously made in the paper strips. Such a strip A having the punch-holes B therein, is schematically illustrated in Figure 8. The

perforations or punch-holes just mentioned extend longitudinally of the strips so that the detached or severed tickets may be conveniently filed and said perforations are utilized 5 for the purpose of registering the superposed strips and for stopping the feed when the end of each ticket or set of tickets has been reached.

In the drawings, 10, represents the side 10 walls and 11, the writing bed or platen that terminates just back of the feeding mechanism, which latter includes a solid roller 12 and having its ends journaled in posts 13 arising from the upper edges of the side- 15 walls. A tubular shaft 14 is journaled in the side walls below the roller 12 and is provided with opposing roller devices that feed the paper strips and also co-operate with the punch-holes in the paper strips for stopping 20 the feed and for registering the superposed strips. These opposing roller devices comprise sleeves 15 that are secured to the tubular shaft preferably one on each side of the center of length thereof, and are each pro- 25 vided with a circumferential flange 16 that is so located as to come into alignment with the punch holes in the strips as they pass through the register. Except when registered with the punch-holes, these roller de- 30 vices are adapted to be in position to feed the paper strips when the apparatus is operated. Intermediate these sleeves the tubular shaft has a collar 17 secured to it, and next to the collar and surrounding the tubular 35 shaft is a peripherally milled annulus 18 having a conical or tapered bore of greater diameter than the shaft 14 so that it will normally hang loose or eccentric on the shaft and therefore out of contact with the 40 upper feed roller 12. This annulus is adapted to be centered on the shaft and brought into frictional contact with said feed roller by a clutch mechanism consisting of a cone 45 19 that points towards the wide end of the bore of the annulus and is mounted on the shaft so as to be reciprocated longitudinally thereon. This clutch cone 19 is secured to the adjacent or inner end of an interior shaft 20, over which the tubular shaft telescopes, 50 by means of a transverse pin 21 that passes through said inner shaft 20 and also through opposite longitudinal slots 22 in the tubular shaft 14. The cone is kept urged towards the annulus by a coiled spring 23 that sur- 55 rounds the tubular shaft between said cone and the adjacent sleeve 15, and the inner shaft 20 to which the cone is secured does not extend out of the tubular shaft but is engaged by a plunger 24 positioned in the 60 tubular shaft and having a head 25 that is slotted longitudinally as at 26, the purpose of which will presently be described. The opposite end of the tubular shaft 14 projects 65 beyond its bearings in the side wall of the register and is provided with an operating

crank 27 by which it may be rotated, while inside the side wall the tubular shaft 14 is operatively connected with the upper feed roller 12 by means of toothed pinions 28 and 29 so that the two will be operated in unison 70 whenever the crank is rotated. The paper feed mechanism is shown in Figure 1 of the drawings in a position where the clutch cone has been operated to center the annulus 18 and position the same in frictional en- 75 gagement with the upper feed roller 12 so that when the crank 27 is rotated by the operator the webs of paper between the periphery of the annulus and said upper feed rollers will have been initially fed far 80 enough to move the punch-holes in the paper out of registry with the flanges 16 of the opposing roller devices. It will be under- 85 stood that when the paper strips are being fed by the upper and lower feed roller de- 90 vices the feed will stop as soon as a pair of punch-holes in the paper come into alignment with or between the respective flanges and the feed roller, and it is to move the paper out of position that the re-starter structure 95 above described is provided whereby the perforations in the paper strips as moved beyond the flanges 16 to permit the latter to operate on the paper strips. When the paper has been moved a distance to insure the clearing of the punch-holes from the lower feed roller devices the annulus 18 is automatically loosened by the withdrawal of the clutch cone, which function may be per- 100 formed in several ways, and for this purpose two types of the mechanism have been herein illustrated, in both of which a cam or worm sleeve is employed in combination with a pawl or finger projecting to the cam from a rock shaft for moving the inner shaft 20 105 in a direction to throw out the clutch elements.

In Figures 1 and 2 of the drawings is il- 110 lustrated a clutch shifting mechanism which comprises a tubular shaft 30 that is journaled in the side-walls 10 below the re-starter shaft, and within said tubular shaft is an inner shaft 31 that is reciprocable longitudinally within the tubular shaft and ar- 115 ranged to rotate therewith. The inner shaft 31 does not extend the entire length of its tubular shaft but terminates about mid-way between the ends thereof where a cam ele- 120 ment is secured to it. This cam element is in the form of a sleeve 32 having external threads 33 and it is connected to the adja- 125 cent end of the inner shaft 31 by means of a transverse pin 34 that passes diametrically through the inner shaft and through oppo- 130 sitely disposed longitudinal slots 35 in the tubular shaft. Collars or stops 36 and 37 are respectively pinned to the tubular shaft upon each side of the cam element, and said cam element is normally urged towards the right in Figure 1 by means of a coiled spring 130

38 surrounding said shaft between said element and adjacent collar or stop 36. When the cam element is released as hereinafter described the spring 38 will force the element towards the collar 37 and move the inner shaft 31 with it, and in order to cushion the impact of stoppage of this cam element a smaller coiled spring 39 is interposed between the collar 37 and the cam element.

10 A rocker-arm 40 is pivotally mounted intermediate its ends upon a bifurcated fulcrum post 41 projecting laterally from the side-wall of the register and said rocker-arm is positioned so that its upper end enters the 15 slot 26 in the head of the plunger 24 and its lower end is disposed in front of and in alinement with the adjacent outer ends of the tubular and inner shafts 30 and 31. Viewing the structure as shown in Figure 1, 20 the reciprocation of the inner shaft 31 towards the left will bring its end into engagement with the adjacent end of the rocker-arm 40 and cause the same to rock, which will move its opposite end inwardly or towards the side-wall of the register thereby 25 forcing plunger 24 into the tubular feed roller shaft 14 and move the inner shaft 20 towards the right (Fig. 1) so that the clutch cone 19 is released and the annulus 18 will 30 be loosened to disengage from the upper feed roller 12 and discontinue feeding the paper so that the flanges 16 will thereafter continue the feed until the succeeding set of punch-holes arrive in registry with the 35 flanges.

The feed mechanism is actuated by the rotation of the crank or handle 27 which rotates the upper and lower feed devices and this rotation is transmitted to the tubular 40 controlled shaft 30 through the medium of an idle gear 42 on a stub spindle 43 projecting inwardly from the adjacent sidewall 10, which gear is in mesh with pinion 28 on the tubular driving shaft and also with a pinion 44 fast on said tubular control shaft 30. The means for moving the inner shaft 31 and the cam element towards the left (Fig. 1) against the action of spring 38 comprises a finger 45 projecting from a collar 46 that 45 is adjustably mounted upon an automatically returnable rock-shaft 47, the latter being journaled in the side-walls 10 and having one end extended through the right hand wall where it is provided with a depressible handle or lever 48. At its opposite end the rock-shaft 47 is surrounded by a coiled spring 49 one end of which is secured to the rock-shaft by a set screw 50 and the opposite end of which is engaged with a pin 51 projecting laterally inwardly from the left hand sidewall. The finger 45 extends tangent to the tubular control shaft 30 and when the cam element is at the limit of its movement to the left (Fig. 1) it will be 55 across the right end of said element, and prevent its movement towards the right but upon the depression of lever 48 said finger is lifted far enough to permit of the passage of the cam element towards the right where it will be under the finger so that the latter will enter the threads 33 of said element upon the releasing of the lever 48. When thus positioned, the inner control shaft 31 will have been withdrawn from engagement with the rocker arm 40 and the 60 spring 23 on the feed drive shaft 14 will push the clutch cone 19 into the bore of the annulus 18 thereby centering the latter and moving the inner drive shaft 20 towards the plunger 24 which is pushed outwardly as 65 shown in Figure 1. The re-starter mechanism is now ready to operate to feed the paper because of the fact that the punch-holes have been previously registered with the feed flanges 16. Upon the rotation of the 70 crank handle 27 the gears will rotate the tubular control shaft 30 and the co-action of the finger 45 with the threads 33 on the cam element will cause the latter to slide along on the tubular shaft towards the left which 75 moves the inner shaft 31 outwardly until its end engages the adjacent lower end of the rocker-arm 40. When the rocker-arm fulcrums on its pivot its upper end will push the plunger 24 inwardly against the end of 80 the inner drive shaft 20 thereby moving the clutch cone 19 out of engagement with the annulus 18 until the latter is released from its frictional engagement with the upper 85 feed roller 12 so that thereafter the feed is 90 taken care of by the flanges and roller until the succeeding set of punch-holes arrive in 95 registry with the lower feed devices or flanges 16.

The record or summary strip is preferably 100 stored or wound upon a re-wind spool having a core 52 mounted upon a spindle 53 that is journaled in the side-walls 10 and having a wide disk-like flange 54 at its end with a ratchet or serrated wheel 55 outside said 105 flange that rotates therewith in the direction of the arrow in Fig. 2. The summary spool spindle 53 extends through its bearing in the side-wall adjacent the crank 27 and its extended end is provided with a gear 56. 110 The tubular control shaft 30 also extends through its bearing in wall 10 and is likewise provided with a gear 57 of approximately the same size as the gear 56 on the 115 rewind spindle. Gear 56 is positioned in a plane close to the side-wall and is in mesh with a larger gear 58 on a stub-shaft 59 projecting from the wall; while gear 57 is positioned in a plane farther from the side-wall so as to mesh with a larger gear 60 120 also mounted upon the stub-shaft 59 beyond the gear 58 and interposed between the gears 58 and 60 are friction disks 58^a and 60^a that are secured to the respective gears and are maintained in frictional contact with each 125 130

other by means of a star-spring 61 that is bowed outwardly as seen in Fig. 1 of the drawings.

Thus it will be seen that should the rewind spool be stopped at any time during the feeding operation the upper and lower feed devices will continue to function regardless of the time when the stoppage of the summary spool takes place. By stopping the rotation of the re-wind spool at the desired time a predetermined length of summary strip may be stored upon the spool and a certain amount of slack will accumulate between the spool and the feed devices. This is accomplished through the medium of a bell-crank that is provided at its hub upon a bolt 62 secured to the side-wall, one of the arms 63 of which bell-crank provides a pawl that extends alongside the wall to the ratchet wheel 55 where it is provided with serrations 64 adapted to be engaged with the teeth of said ratchet wheel. The other arm 65 of said bell-crank extends upwardly from the pivot and a coiled spring 66 is connected to it, with the opposite end of the spring secured to a set-screw 67 so that the pawl arm 63 is urged normally towards the ratchet wheel 55. A lateral finger 68 projects horizontally away from the hub of the bell-crank into the path of a projection in the form of a set-screw 69 that adjustably secures a collar 70 to the rock-shaft 47, so that when the lever 48 is depressed to render the re-starter operative and set the cam-sleeve the projection 69 will push down the lateral finger 68 and rock the bell-crank so as to raise the end of the pawl arm 63 from the ratchet wheel 55. The crank 27 may be now rotated which feeds the paper strips across the platen and out of the discharge end of the register, and as soon as the finger 45 moves to the end of the cam-sleeves 32 and drops off the same to the tubular control shaft 30, the shaft 47 will be rocked which will release the projection from the finger 68 of the bell-crank so that the latter will be operated by its spring 66 to move the pawl 63 to engage the ratchet wheel and thereby stop the rotation of the re-wind spool. The operator of course continues to turn the operating crank 27 but no further rotative movement will be imparted to the re-wind spool which has been stopped and the gears 56 and 58 and the friction disk 58^a will remain stationary but the other gears and friction disk will continue to rotate until the crank has stopped. During this further operation of the crank the upper and lower end devices 12 and 16 will continue to feed out the strips until the succeeding set of perforations come into registry with the flanges whereupon the further feed of the strips will be stopped. This continued feed of the strips after the re-wind spool has been stopped will create

a quantity of slack in the summary strip between the feed mechanism and its spool and thereby prevent a pull on the summary strip.

Another form of mechanism for controlling the rewind spool of the summary strip is illustrated in Figs. 5, 6, and 7 of the drawings. In this latter structure the upper and lower feed devices, the outside gearing for transmitting motion to the summary spool, and the re-starter mechanism, are identical 70 or substantially the same as that above described in connection with the type disclosed in Figs. 1 to 4 of the drawings. In the modified type the rocker arm 40 is dispensed with, and the rock-shaft 47 is positioned in 75 approximately the horizontal plane of the tubular shaft 14 of the lower feed devices as seen in Fig. 6 which shows both ends of said rock-shaft are extended beyond its 80 bearings. The left hand extension of the 85 rock shaft 47 has a finger 71 secured to it which is of the same construction as finger 45 of the first described structure, and a coiled spring 72 surrounds said left hand extension with one of its ends bent over and 90 pressing against the inner portion of the finger and the opposite end secured to a set screw 73 that is screwed into the adjacent 95 side-wall 10 so that the rock-shaft may be automatically returned to its normal position. The opposite extension of the rock shaft has the depressible lever 48 secured to it and extending downwardly from the boss of the lever is a lug 74 that projects beyond 100 a transverse pin 75 on the upper portion of the vertical arm 65 of the bell-crank that projects through a segmental slot 76 in the side-wall of the casing. When the depressible lever 48 is moved downward the lug 74 will engage the pin 75 and move the same 105 towards the opposite end of the slot 76 thereby rocking the bell-crank and lifting the pawl arm 63 thereof off the ratchet wheel 55 of the re-wind spool.

The end of the tubular drive shaft 14 opposite the crank 27 is extended through its bearing in the side-wall as shown at the left in Figure 5, and the extended portion is provided with longitudinal slots 77. The cam element is slidably mounted on the extended end of tubular shaft 14 by a transverse pin 34^a that passes through and is guided by the slots 77. The cam element is in the form of a sleeve 32^a having threads 33^a thereon, which threads are engaged by 115 the finger 71 against which the finger is urged by the spring 72.

Within the tubular drive shaft 14 of this modified structure there is mounted a solid shaft 78 that is adapted to be reciprocated 120 longitudinally and is also rotated with the tubular shaft, and said solid shaft is long enough to extend from beyond the clutch cone to the cam element on the outer extended end of the tubular shaft, to which 125 130

cam element it is secured by the transverse pin 34 so that when the cam element slides upon the tubular shaft said solid shaft will likewise be reciprocated. The solid shaft 5 adjacent its opposite or inner end is provided with a longitudinal slot 79 which is in registry with the slot 22 in the tubular shaft and the pin 21, which passes through the clutch cone 19, also passes through said 10 slot 79 so that when the cam element has moved the solid shaft 78 longitudinally a certain distance to the right the end of the slot 79 will engage the transverse pin 21 and move the clutch cone away from the annulus 15 18 to disengage the latter from the paper strip to render the restarter inoperative. A light coiled spring 80 is interposed between the inner end of the solid shaft 78 and the inner end of the tubular portion of shaft 14 20 so as to normally urge the solid shaft towards the left, and for the purpose of predetermining the distance the solid shaft will move outwardly or to the left a set-screw 81 is screwed into the tubular shaft. By turning 25 the set-screw inwardly or outwardly in the tubular shaft as will be understood an adjustable stop is provided for the cam element and the inner shaft which stop will determine the relative starting position of 30 the cam element with respect to the finger 71 and will consequently predetermine the point when the pawl arm 63 will be dropped to the ratchet disk 55 to stop the rotation of the re-wind spool for the summary strip. 35 This will be the moment the finger rides off the threads and positions itself in front of the outer end of the cam element. By the arrangement described a greater or less amount of slack may be provided in the summary strip between the feed devices and the 40 re-wind spool.

What we claim is:

1. In an autographic register co-acting strip feeding devices including a drive-shaft that are adapted to feed a plurality of strips, a starting mechanism adapted to initially feed the strips, a spool for re-winding one of the strips, gears actuated by the drive-shaft for rotating said spool certain of said gears being frictionally related, a cam element rotated by said shaft, a depressible finger engaging said cam for causing the latter to move longitudinally whereby to render the starting mechanism inoperative upon the strips, and means connecting said finger and said spool and controlled by the movement of the finger to stop the rotation of the latter. 45
2. In an autographic register co-acting strip feeding devices including a drive-shaft that are adapted to feed a plurality of strips, a starting mechanism adapted to initially feed the strips, a spool for re-winding one of the strips, gears actuated by the drive-shaft for rotating said spool element two of 50
3. In an autographic register co-acting strip feeding devices, including a drive-shaft, that are adapted to feed a plurality of strips, a starting mechanism adapted to initially feed the strips, a spool for re-winding one of the strips, means for rotating said spool operatively connected with said drive-shaft, a cam element rotated by said shaft, an oscillatory finger engaging 55 said cam for causing the latter to move longitudinally whereby to render the starter mechanism inoperative upon the strips, and means connecting with said finger and said spool and operated by the finger to stop the rotation of the spool upon the rendering of the starting mechanism inoperative. 60
4. In an autographic register co-acting strip feeding devices, including a drive-shaft, that are adapted to feed a plurality of strips, a starting mechanism adapted to initially feed the strips, a spool for re-winding one of the strips, means for rotating said spool operatively connected with said drive-shaft, a cam element rotated by 65 said shaft, an oscillatory finger engaging said cam for causing the latter to move longitudinally whereby to render the starter mechanism inoperative upon the strips, and means connecting with said finger and said spool and operated by the finger to stop the rotation of the spool upon the rendering of the starting mechanism inoperative. 70
5. In an autographic register co-acting strip feeding devices, including a drive-shaft, that are adapted to feed a plurality of strips, a starting mechanism adapted to initially feed the strips, a spool for re-winding one of the strips, means actuated by the drive-shaft for rotating said spool, a cam element rotated by said shaft, an oscillatory finger engaging 75 said cam whereby to cause the latter to move longitudinally and render the starter inoperative to move the strips, a rock-shaft upon which said finger is mounted, and means controlling the rotation of said spool and operated by the movement of said rock-shaft. 80
6. In an autographic register coacting feed rollers adapted to move a plurality of strips, initially operative feed devices co-actively related with one of said rollers and 85

including a reciprocable shaft, a spool for rewinding one of the strips, means operatively connecting said feed rollers with said spool to rotate the latter, a cam element 5 operated by said means, devices for stopping the rotation of said spool, a reciprocable shaft connected with cam element, and means operatively connecting said shafts, whereby the reciprocation of the cam element shaft, operates the first mentioned shaft to render the initial feed devices inoperative upon the strips.

7. In an autographic register coacting feed rollers adapted to move a plurality of strips, 15 initially operative feed devices coactively related with one of said rollers and including a reciprocable shaft, a spool for rewinding one of the strips, means operatively connecting said feed rollers with said spool to 20 rotate the latter, a cam element operated by said means, devices for stopping the rotation of said spool, a reciprocable shaft connected with said cam element, and a rocker-arm fulcrumed intermediate its ends and 25 having its ends coactively related with said reciprocable shafts whereby the reciprocation of the cam element shaft operated the first-mentioned shaft to render the initial feed devices inoperative upon the strips.

8. In an autographic register coacting feed rollers adapted to move a plurality of strips, initially operative feed devices coactively related with one of said rollers and including a reciprocable shaft, a spool for rewinding one of the strips, means operatively connecting said feed rollers with said spool to rotate the latter, a rotatable tubular 35 shaft, a cam element rotatable with said tubular shaft and reciprocable thereon, a

shaft within said tubular shaft and connected to and reciprocable with said cam element, a depressible finger for reciprocating said cam element, means connected with said finger for stopping the rotation of said spool, and means operatively connecting said reciprocable shafts whereby the reciprocation of said cam element moves said first-mentioned shaft longitudinally to render the initial feed devices inoperative upon the strips. 50

9. In an autographic register coacting feed rollers adapted to move a plurality of strips, initially operative feed devices coactively related with one of said rollers and including a reciprocable shaft, a spool for rewinding one of the strips, means operatively connecting said feed rollers with said spool to rotate the latter, a rotatable tubular shaft, a cam element rotatable with said tubular shaft and reciprocable thereon, 55 a shaft within said tubular shaft and connected to and reciprocable with said cam element, a depressible finger for reciprocating said cam element, means connected with said finger for stopping the rotation of said spool, and a rocker-arm fulcrumed intermediate its ends and having its ends coactively related to said reciprocable shafts whereby the reciprocation of the cam element shaft causes the first-mentioned shaft to move 60 longitudinally and render the initial feed devices inoperative upon the strips. 65

Signed at Chicago, in the county of Cook, and State of Illinois, this 6 day of January, 1926.

LOUIS JENSEN.
CHARLES L. WINTER.
